UNITED STATES PATENT OFFICE.

FREDERICK RICHARD SIMMS, OF WILLESDEN LANE, ENGLAND, ASSIGNOR TO SIMMS MAGNETO CO., INC., OF NEW YORK, N. Y.

ELECTRIC IGNITION APPARATUS.

1,083,222.

Specification of Letters Patent. Patented Dec. 30, 1913.

Original application filed December 10, 1910, Serial No. 596,638. Divided and this application filed July 22, 1912. Serial No. 710,940.

To all whom it may concern:

Be it known that I, FREDERICK RICHARD SIMMS, a subject of the King of Great Britain, residing at Welbeck Works, Kimberley 5 Road, Willesden Lane, Middlesex, England, have invented new and useful Improvements in Electric Ignition Apparatus, of which the following is a specification.

This invention relates to electric ignition 10 apparatus of the kind in which a magneto-electric machine having an armature in the form of an induction coil and provided with a circuit breaker, has combined with it an external source of current, a trembler coil 15 and controlling switch, the latter being so arranged that the induction coil can be brought under the influence of either the magnetic field of the magneto or of the current from the external source for ignition 20 purposes, or cut off from both.

According to my invention I provide an auxiliary circuit breaker for use when the external current source is used for ignition, the said auxiliary circuit breaker being arranged 25 so that the circuit through the said external source is open when the main circuit breaker is closed, thus avoiding short circuiting the primary winding of the induction coil. In 30 a suitable arrangement for carrying out the invention this auxiliary circuit breaker is arranged between the said external current source and primary winding and in the case where the main circuit breaker is in the form 35 of a rotating arm carrying a brush designed to make and break contact with one fixed contact piece, or a series thereof, in circuit with the said primary winding, it embodies the application to the said arm of another brush designed to make contact with another 40 fixed contact piece, or a series thereof, in circuit with the said external current source.

To enable the invention to be fully understood, I will describe it by reference to the accompanying drawing, in which:—

45 Figure 1 is a diagrammatic view illustrating electric ignition apparatus, for a four cylinder internal combustion engine, embodying my improvements, and including a controlling switch of the kind described in 50 my application for a patent Serial No. 596,638, of which this application is a division, the parts of the apparatus being shown in position for utilizing the external

source of current for ignition purposes. Figs. 2 and 3 are similar views to Fig. 1, 55 but respectively showing the parts in position for utilizing the magneto for ignition purposes and for cutting out both the said magneto and external source of current.

a is the armature of the magneto and *b, c* 60 respectively the primary and secondary coils thereon, *d, d, d, d* are the sparking plugs, one element of each of which is in connection with a brush *e* bearing upon the usual high tension distributor *f* in connection with one 65 end of the secondary coil *c* and the other element of which is in connection with the other end of the said coil as indicated by the dotted line or earth connection.

g, g are the contact pieces with which the 70 brush *h* on the rotating arm *i* makes and breaks contact when the magneto is operating and *j* is the condenser in connection therewith, the said contacts and brush constituting the main circuit breaker. 75

k is the external source of current in the form of an accumulator or battery and *l* is the spring armature or trembler designed to be attracted by the electro-magnet *m* which is in circuit with the said battery. 80

n is the adjustable screw for making contact with the trembler *l* and *o* is a condenser in connection with the coil of the magnet *m* for reducing sparking at the point of the 85 said screw.

1, 2, 3, 4, and 5 are the terminals or contact pieces of the controlling switch described in the application above referred to, 1 and 2 being respectively connected to the positive and negative poles of the battery *k*. 90 The terminal 4 is connected to one end of the primary coil *b* while the terminal 5 is connected to earth, as indicated by the dotted line *p*; *q* are forked contacts forming the rotatable portion of the controlling 95 switch but insulated from each other, the said forks being designed to make contact with the contact pieces 2, 3, 4, 5 as herein-after described.

r, r are the contact pieces of the auxiliary 100 contact breaker arranged concentrically with the pivot of the arm *i* and *s* is the brush carried by the said arm to make contact with the said contact pieces, the said pair of contact pieces *r, r* being so arranged relatively to 105 the pair of contact pieces *g, g* of the main

contact breaker that the arm is never in circuit with both pairs of contacts simultaneously.

In the operation of the mechanism with the switch in position for effecting ignition by the battery *k*, as indicated in Fig. 1, the current passes from the said battery to the primary coil *b* of the magneto, and thence to a sparking plug, the current flowing by way of the magnet *m*, trembler *l*, screw *n*, fork *p*, contact 4, line 6, coil *b*, earth connections 7, 8 and 9, arm *i* brush *s*, either contact *r*, line 10, contact 3, fork *q*, contact 2 back to battery *k*. By operating the switch so as to bring one of the limbs of the fork *q* on to contact 3 and the limbs of the fork *p* into an intermediate position as shown in Fig. 2 the magneto only supplies current for sparking purposes in the usual manner, the main contact breaker *i*, *h*, *g* then functioning instead of the auxiliary contact breaker *i*, *s*, *r*. For cutting out both the battery and the magneto the switch is operated to the position shown in Fig. 3 in which the limbs of the fork *q* are out of contact with the contacts 2 and 3 and the limbs of the fork *p* in contact with the contacts 4 and 5 whereby the primary coil *b* of the magneto is short circuited.

30 By the described arrangement of auxiliary contact breaker it will be evident that when the switch is in position for effecting ignition by the battery *k* the circuit through the said battery will be maintained open when the main circuit breaker *i*, *h*, *g* is closed, thus avoiding short circuiting the primary coil *b* which latter would take place if the two circuit breakers were both closed at the same time. It will also be evident that the ignition effected by the battery *k* will be slightly later than that by the magneto.

Claims:

1. An electric spark producing apparatus comprising an induction coil, means for pro-

ducing a magnetic field within which the said coil may rotate, an external source of current to excite the primary winding of said induction coil, and a trembler in circuit with said external source of current, a main 50 circuit breaker for said primary winding, an auxiliary circuit breaker interposed between said external source of current and the primary winding and constructed to maintain the circuit through said external 55 source of current open when the said main circuit breaker is closed.

2. In an ignition system provided with igniting devices, a high tension magneto, a main circuit breaker for the primary circuit of the magneto, an external source to excite the primary winding of the magneto, an electric trembler in circuit therewith and an auxiliary circuit breaker adapted to be inserted in circuit between the accumulator 60 and the primary circuit, said auxiliary circuit breaker being constructed to hold the accumulator circuit open while the main circuit breaker contacts are closed, and a switch 65 for connecting either the magneto circuit or the accumulator circuit with the ignition system.

3. In an ignition system provided with igniting devices, a high tension magneto, a main circuit breaker for the primary circuit thereof having a rotary part, an accumulator a trembler in circuit therewith an auxiliary circuit breaker therefor having a rotary part operatively connected with the circuit breaker in a predetermined relation 70 so that the auxiliary circuit breaker will hold the accumulator circuit open while the contacts of the circuit breaker are closed, and a switch for throwing the magneto circuit or the accumulator circuit into action. 75 80 85

FREDERICK RICHARD SIMMS.
